SPOOL FOR WIRE-STRANDING MACHINES

Stephen Krizsan, Jr., Trenton, N. J.

Application May 10, 1944, Serial No. 534,943

4 Claims. (Cl. 242—118)

1

This invention relates to a spool for wire stranding machines, and it aims to provide a means which will simplify and expedite the spooling of wire in such machines, and one which will speed up production in assembly.

A further object is to provide a novel construction wherein the spool is made in interfitting separable sections having adjustable means to position the spool of wire and which also functions to hold the sections together and against separation, and further to provide in connection with the spool, novel braking mechanism.

The more specific objects and advantages will become apparent from a consideration of the description following taken in connection with accompanying drawings illustrating an operative embodiment.

In said drawings:

Figure 1 is a view in side elevation showing my improved spool in place in the frame of a wire stranding machine;

Figure 2 is a vertical sectional view taken on the line 2—2 of Figure 1;

Figure 3 is a vertical sectional view taken on the line 3—3 of Figure 2;

Figure 4 is a vertical sectional view taken on the line 4—4 of Figure 2, and

Figure 5 is a horizontal section taken on the line 5—5 of Figure 2.

Referring specifically to the drawings wherein like reference characters designate like or similar parts throughout the different views, the spool has two main sections 10. Each section 10 has a relatively large disc or flange 11 provided with a hub at 12. Such hubs at the inner ends have pairs of projections 13 which are interfitted with each other and the outer ends of the hubs 12 are formed as trunnions 13' which are journaled in side members 14 of the frame 15 of a wire spooling machine.

A coil of strand wire (not shown) is located between the discs or flanges 11 and on bars 16 of any desired number which are adjustably mounted to assume different positions radially according to the size of the coil to be supported. Such discs 11 preferably have radial slots 17 therein and the bars 16 have screw threaded shanks or terminals 18 located in the slots for adjustment. Nuts 19 are threaded on the shanks 18 outwardly of the discs.

The spool is mounted in the side members 14, as will be realized, for rapid rotation during the stranding operation and suitable braking means may be provided on the spool. To this end, a brake drum 20 is mounted on either corrugated

2

seat 21 of the hubs 12 so as to be rigid on the spool and to rotate therewith.

An expandable and contractile brake band 22 surrounds the drum 20 preferably having an inner rib 23 located in a peripheral groove 24 of the drum. This band is fastened at 25 to the frame 15 at one terminal, while the other terminal is free. Anchored to a stud 26 in the fixed terminal of the brake band is a contractile coil spring 27 carried by a screw member 28 passing through a bifurcation or slot 29 in the free terminal of the brake band and above which a nut 30 is screwed onto the bolt 28 for adjustment to vary the tension of the spring 27 and control the action of the brake band accordingly.

In using the invention, the workman or spooler, with the sections 10 disengaged, sets the coil or bundle of wire on one of the sections about the bar 16 and then secures the other section to the first section through proper adjustment and tightening of nuts 19, and then places the spool with the assembled coil or bundle of wire thereon in the frame 15. The machine will accommodate both fine and heavy wires and the method of spooling is expeditious and will overcome the necessity of stranding machines having to wait hours as is necessary under present conditions, incidental to the mounting or assembly of the bundle or coil onto a spool.

It will be noted that the sections have a bore 31 therethrough. This enables a bar or rod to be passed therethrough when desired, and especially in handling or supporting either of the sections when detached from the other.

Various changes may be resorted to provided they fall within the spirit and scope of the invention.

I claim as my invention:

1. A structure of the class described comprising hubs, opposed projections on the hubs separably engaged with one another, said hubs having integral discs, bars securing the discs together, and means clamping the bars to each disc for adjustment radially with respect to the discs, said bars and clamping means dually functioning as a bundle support and for retaining the hubs in engagement.

2. A spool of the class described having parts provided with hubs, the inner opposed ends of said hubs having projections, said projections being separably interfitting, discs integral on said hubs provided with radial slots, bars spanning the discs, said bars having shanks extending through the slots, and securing nuts on the

3

shanks to clamp them to the discs to form an adjustable bundle support and detachable fastening means for retaining the hubs in interfitted engagement.

3. A spool of the class described having parts provided with hubs, the inner opposed ends of said hubs having projections, said projections being separably interfitted, discs integral on said hubs provided with radial slots, bars spanning the discs, said bars having shanks extending through the slots, securing nuts on the shanks to clamp them to the discs, a frame, a brake drum on one of the hubs, a brake shoe carried by said frame operatively associated with said drum, and trunnions on said hubs to enable mounting in a frame, said bars and nuts forming an adjustable bundle support and a detachable connection for the hubs.

4. A spool of the class described comprising a

4

pair of parts, said parts each including a hub having projections on its inner end, said projections being interfitted for keying the parts to one another, a disc integral with each hub and having a plurality of radial slots, bars spanning the discs and slidably engaging the slots to form a bundle support, clamping means for adjustably clamping the bars to the discs for varying the size of the bundle support and for securing the hubs in interfitted engagement, one of said hubs having a toothed portion adjacent its outer end, a brake drum having a part in interfitted engagement with the toothed portion, trunnions on the outer ends of the hubs, a frame in which the trunnions are journaled, and a brake shoe yieldably and adjustably supported by the frame and engaging over the brake drum.
